VACUUM CLEANER

Charles L. Brown, Jr., Stamford, Conn., assignor
to Electrolux Corporation, Dover, Del., a cor-
poration of Delaware

Application January 27, 1938, Serial No. 187,149

5 Claims. (Cl. 200—52)

My invention relates to vacuum cleaners and more particularly to a means of mounting a switch in a vacuum cleaner casing.

An object of my invention is to provide an improved mounting for a vacuum cleaner switch to facilitate the assembly and removal of the switch.

Another object of my invention is to provide an enclosing casing for a switch harmonizing with the general design of the vacuum cleaner and permitting ready access to the switch.

What I consider to be novel and my invention may be better understood by reference to the following specification and appended claims when considered in connection with the accompanying drawing, in which

Fig. 1 is a side view of a vacuum cleaner incorporating my improved switch mounting;

Fig. 2 is a sectional view of the switch mounting;

Fig. 3 is a sectional view taken along the line 3—3 of Fig. 2;

Fig. 4 is a perspective view of the mounting strap;

Fig. 5 is a perspective view of a locking key;

Fig. 6 is a view partly in section showing one step in the assembly of the switch and cover; and

Fig. 7 is a bottom view of the devices shown in Fig. 6.

Referring to the drawing, 10 indicates a vacuum cleaner unit connected to a cleaning tool 11 by means of a flexible hose 12 with or without a substantially rigid tubular handle member 13.

Vacuum cleaner unit 10 is of the type that may be moved around the surface on which it is supported by pulling on the flexible hose 12. For controlling the operation of the vacuum cleaner unit 10, switch 14 is provided mounted in a rear end housing 15. As best indicated in Fig. 2, switch 14 is provided with a button 16 which may be operated by foot pressure to control the operation of the vacuum cleaner unit 10. Leads 17 are connected to the switch 14. Two male terminals 18 are provided for connection to a source of electrical supply.

Switch 14 is secured in an opening 19 in rear end housing 15 by means of a U-shaped strap 20. Strap 20 is secured to switch 14 by means of a screw 21 in threaded engagement with a nut 22 located within the body of switch 14. As may be seen by reference to Fig. 2, a handle 23 is connected to a ring 24 by means of a pin 25. A cover plate 26 harmonizing with the general design of the vacuum cleaner and presenting a smooth exterior encloses the portion of switch 14 which extends above the surface of housing 15 and is

provided with two projecting arms 27 which surround the opposite sides of the handle pin 25. The switch button 16 extends through an opening 28 in cover plate 26. A ferrule 29 is secured to cover plate 26 and extends around a portion of the terminals 18 to provide a smooth path for the entrance of a connector, not shown, for completing connections with terminals 18 and a source of electrical supply.

Switch 14 is provided with two side projections 30 and an end projection 31. Cover plate 26 is provided in the bottom with two inwardly extending shoulders 32. Shoulders 32 are adapted to rest on shoulders 33 integral with the housing 15 around the opening 19. Two U-shaped locking keys 34 are positioned between the shoulders 32 of the cover plate 26 and the side projections 30 of switch 14.

As best indicated in Figs. 6 and 7, the switch 14 and the cover plate 26 are assembled together by first depressing the button 16 and passing the switch from the left to the right as shown in Fig. 6 with the projections 30 of the switch 14 positioned above the shoulders 32 of cover plate 26. Switch 14 is moved to the right until the button 16 is in line with the opening 28. The switch 14 is then moved upwardly until the top of the switch engages the top surface of the cover plate 26. The two locking keys 34 are inserted between the projections 30 and the cover plate shoulders 32, locking switch 14 and cover plate 26 together. The assembly of the switch 14 and the cover plate 26 is inserted in the opening 19 of housing 15. The U-shaped strap 20 is inserted over the switch 14 within housing 15 with the bottom of the U seated in a groove 35 in the bottom of switch 14. Screw 21 is passed through an aperture 36 in strap 20 and threaded into engagement with nut 22. The leads 17 are preferably connected to the switch 14 before it is secured to the housing 15. However, it is possible to connect the leads 17 at any step in the assembly of the switch 14 that may be desired. When the screw 21 is tightened, the strap 20 engages the bottom of shoulders 33 of housing 15 pulling the shoulders 32 of cover plate 26 down against the shoulders 33, and also drawing the end projection 31 of switch 14 down against the housing 15 at 37 as shown in Fig. 2. To remove the switch 14 it is simply necessary to loosen the screw 21 and remove the strap 20. The leads 17 may then be disconnected from switch 14 and the switch removed from the housing 15. The cover plate 26 may be removed from the switch 14 by removing the locking keys 34. The button 16 is depressed and the switch 14 moved

to the left, as shown in Fig. 2, until the side projections 30 are free of the shoulders 32. The cover 26 may then be lifted from the switch 14.

What I claim is:

- 5 1. In a vacuum cleaner, a housing having an opening, a switch mounted in said opening, a switch cover surrounding the portion of said switch extending beyond said housing, means for locking said cover to said switch, and a U-shaped strap secured to said switch and engaging the inside of said housing for securing said switch and said cover to said housing.
- 10 2. In a vacuum cleaner, a switch having projections, a switch cover having inwardly turned shoulders, U-shaped locking keys located between said switch projections and said cover shoulders for securing said cover to said switch, a housing having an opening to receive said switch, and a strap secured to said switch engaging said housing for securing said switch and said cover to said housing.
- 15 3. In a vacuum cleaner, a housing having an opening, a switch mounted in said opening having end projections resting on said housing and side projections, a cover for the portion of said switch extending beyond said housing having inturned shoulders, keys located between said switch projections and said cover shoulders for locking said switch and cover together, leads connected to

said switch, and a U-shaped strap secured to said switch and engaging said housing for rigidly securing said switch and said switch cover to said housing.

4. In a vacuum cleaner, a housing having an opening, a switch mounted in said opening having an end projection resting on said housing and side projections, a cover surrounding a portion of said switch extending beyond said housing having inturned shoulders and an opening, a switch button passing through said cover opening, locking keys located between said cover shoulders and said switch side projections, leads connected to said switch, and a U-shaped strap secured to said switch and engaging said housing for securing said switch and said cover to said housing.

5. In a vacuum cleaner, a housing having an opening, a switch mounted in said opening and having a portion extending beyond said housing, side projections extending from said switch without said housing, a cover for the portion of said switch extending beyond said housing having inturned shoulders, keys located between said switch projections and said cover shoulders for locking said switch and cover together, and means for securing said switch and said switch cover to said housing.

CHARLES L. BROWN, JR.
